UNITED STATES PATENT OFFICE.

GUSTAV TRINKLER, OF LINDEN, NEAR HANOVER, GERMANY.

INTERNAL-COMBUSTION ENGINE FOR LIQUID COMBUSTIBLE.

No. 828,352.

Specification of Letters Patent.

Patented Aug. 14, 1906

Application filed October 15, 1903. Serial No. 177,221.

To all whom it may concern:

Be it known that I, GUSTAV TRINKLER, a subject of the Emperor of Russia, whose post-office address is No. 8 Egestorfstrasse, Linden, near Hanover, Kingdom of Prussia, German Empire, have invented a new and useful Internal-Combustion Engine for Liquid Combustible, of which the following is a specification.

It is well known that for working internal-combustion engines under economical conditions it is necessary to subject the air to a very high degree of compression. For rendering this possible pure air is first supplied to the cylinder through the air-admission valve, and then the combustible is admitted by a special valve. Toward the end of the compression period the combustible is rapidly mixed with the total quantity of air, which, compressed to about twenty atmospheres, has attained a temperature sufficient to ignite the mixture. The mixture will now by its expansion push the engine-piston forward.

The present invention now relates to devices for effecting the mixture of the combustible with the compressed air. A machine provided with this mixing mechanism is represented in the annexed drawings, on which—

Figure 1 is a side view, partly in section, of a four-cycle combustion-engine. Fig. 2 is a plan, and Fig. 3 a rear view, of the same machine. Fig. 4 shows part of the mechanism in detail. Fig. 5 shows in vertical section a modified arrangement of the locking mechanism. Fig. 6 shows another modification of this mechanism. Fig. 7 the subject of the present invention adapted to be applied to a two-cycle combustion-engine. Fig. 8 shows in detail a part of the mechanism.

Referring to Figs. 1 to 4, A is the cylinder, in which moves the working piston B. A' is the connecting-rod of the power-piston acting on the crank-shaft B'. C' is the fly-wheel, D' the pulley, and E' the machine-frame. C is the valve-head, with the inlet-valve F' and the outlet-valve G'. The valves F' and G' are actuated from the valve-gear shaft J', which makes half the number of revolutions of the main shaft B' by tappets provided on said shaft J' and levers H' H'. The valve-gear shaft J' receives its rotation from the main shaft B' by the intermediate shaft K' and two pairs of bevel and worm wheels. The fluid combustible is supplied in any convenient way—for instance, by a pump (not shown)—through pipe D and return-valve E to the chamber F, where it collects. The air admitted through the valve F' arrives during the compression period through the compensating passage G into the space in front of the auxiliary piston H, moving in the chamber L. This piston is so controlled that during the time of the compression period it remains stationary, or almost so. The pressure in front of the piston is the same as the pressure in the compression-chamber. The fluid combustible in the chamber F remains also motionless, for the reason that the air-pressure acting on the same through the openings K and M is compensated; nor can the combustible ignite at too early a period in the very small chamber F. Toward the end of the compression period the auxiliary piston H is rapidly moved outward. In this movement it closes the compensating passage G and increases the pressure in the chamber L in front of the piston. The air in consequence thereof rapidly rushes through the passages M and K into the combustion-chamber, carrying with it the combustible contained in the chamber F for mixing the same with the air in the compression-chamber. The piston-rod J of the piston H is actuated by the two-armed lever N O, keyed on shaft P. The arm O is connected by the rod Q with the two-armed lever S, provided at its lower end with roller T. V (shown in Fig. 4 in detail) is a locking-lever pivoted at U and bearing on the roller T. This locking-lever is drawn against the lever V by the spring W. This arrangement prevents the piston H to be driven outward by the compressed air, in the compression-chamber of which the chamber L forms a part. The piston being provided with a piston-rod has a smaller surface on the side to which the piston-rod is attached. The larger power exerted by the compressed air on the larger surface on the opposite side is taken up by the locking-lever V and the spring W. The tension of the spring W is adjusted so as to take up only the excess of air-pressure exerted on the larger surface of the piston H; but when the tappet X, secured to the driving-shaft B' of the engine, acts on the roller Y to move the lever S the tension of the spring W is overcome, the roller T moves the locking-lever V upward, and unlocks the piston H. At this moment the piston H will be rapidly driven outward by the explained ex-

cess of pressure acting on the larger piston-surface. The whole system H J N O Q S can in this way be operated by the compressed air alone provided the piston-rod is of the 5 thickness as to sufficiently reduce the area of the piston-face to which it is attached. The tappet X merely follows the movement of the roller Y from the moment the roller T is released; but if the engine runs at a high 10 speed or if a thin rod J is attached to the piston H the air displaced by the movement of the piston H does not rush rapidly enough through the passage K. In that case the tappet X has in its further course after the 15 release of the roller T a relatively higher speed than the air rushing through K and acts positively on the piston H by the system S T Q O N J. This arrangement is shown in Figs. 1 to 4 of the drawings. The position 20 represented in Fig. 1 corresponds to the beginning of the period in which the liquid combustible is injected into the compressed air. When the tappet has passed the roller Y, the injection has taken place. The whole 25 system H J N O Q S remains during the power-stroke and the next return stroke in the position reverse to that shown on the drawings. When the following suction-stroke commences, the tappet X again approaches the roller Y; but as at this time the roller is still in the reverse position it goes past without touching it. At about the middle of the suction-stroke the tappet Z on the 30 valve-gear shaft J', which shaft makes half the number of revolutions as the driving-shaft B', begins to act on the roller L', fixed to the arm O of the lever O N, which at this time is still, as above explained, in the position reverse to that shown in Fig. 1. It pushes the 35 arm O outward, and thereby brings the whole system in the position originally described, with the locking-lever V bearing on the roller T. It is also possible to move the piston H from a strong shaft positively and 40 at a high speed.

Fig. 5 shows in a section through the valve-head of the engine a modified arrangement, the same reference-letters designating similar parts as in the first figures. The piston-rod J is very thick, as in this arrangement the piston H is to be driven outward by the compressed air alone. The right-hand arm of the lever N O bears upon the locking-lever N', pivoted in M'. The piston H is thereby 45 locked and prevented from moving during the compression period. At the end of the compression period the tappet O', acting on the roller P', moves the locking-lever away from the arm O, releases the lever N O, and 50 allows the piston H to be driven outward by the compressed air to inject the fluid combustible into the compression-chamber, as before described. After this injection-stroke of the piston H the tappet O' or another tap- 55 pet, which in that case must be in another

plane, approaches the roller L', provided on the arm O of the lever N O, and by depressing this lever brings the whole system again back in its original position, the locking-lever N' being pressed by the spring Q in the position to lock the lever N O and piston H. This locking mechanism differs from that described above with reference to Fig. 1 by the pressure of the lever N O being directly transmitted to the pivot M' and the locking-lever N' being released by the tappet O'. 70 75

Fig. 6 shows a modification of this mechanism. J' is again the valve-gear shaft, and N O the lever keyed on the shaft P, the end of the arm O of this lever being jointed to the pivot M' by the toggle-lever M' R' S'. This toggle-lever is by spring Q' suspended on the pivot U', pressed against the cam-disk V. The part W' to X' of this cam-disk is round. It corresponds with the compression period 85 of the working piston, and as at this time the pressure acting on the larger face of the piston H tends to move the lever N outward and the arm O upward the roller P' is so more firmly pressed against the cam-disk. At 90 about the end of the compression period the part X' Y' of the cam-disk moves the roller P' away from the disk, the toggle-joint bends out, and the lever N O, together with the toggle-lever, assumes the position Z' Z' M', 95 (shown on the drawings in dotted lines,) in which position the piston H has made its outward stroke. On the further movement of the cam-disk the cam W' X' Y' meets the roller L' of lever N O, depresses the arm O, 100 and restores the original position. It is a matter of course that two cam-disks may be arranged instead of one for acting on the rollers P' and L'.

Figs. 7 and 8 show a mechanism for actuating the piston H which is especially adapted for two-cycle combustion-engines and which also in the drawings is shown as applied to such an engine. The corresponding parts are again marked with the same reference-letters as in the other figures. The working cylinder A is closed at the end opposite to the compression-chamber, and this side of the cylinder is made to serve as air-pump. The working piston is connected with the main 110 shaft B' by piston-rod A², cross-head B², and connecting-rod A'. The piston on its inward stroke draws in pure air by the valve C². On its outward stroke it compresses the same to about 0.3 atmospheres. Toward 115 the end of the outstroke the working piston opens the exhaust-port D², through which escape the spent gases. At this time also the air-port E² is laid free, and the partly-compressed air flows from the chamber in 120 front of the piston to the rear of the same and guided by the projection F², provided on the face of the piston, sweeps the products of combustion out of the combustion-chamber. This part is not of my invention. It is one of 130

the known methods of operating two-cycle combustion-engines; but it is to be understood that my invention which I shall now particularly describe is not applicable to this 5 class of two-cycle combustion-engines alone, but also to others—for instance, to those in which a special pump is provided for introducing compressed air into the working chamber of the cylinder, in which, therefore, the cylinder is not closed in front of the piston. The present arrangement is distinguished by the operation of the piston H by means of the three-armed lever S, provided with two rollers Y and L'. During the 10 compression period the piston H is locked by the roller L' of the lever S, bearing against the cam-disk Z, secured to the driving-shaft. The lever S is, as before described, connected with the rod J of the piston H by rod Q and lever N O. At this time the round part G² to H² of the cam-disk bears against the roller L' and locks the piston H. The compensating passage G remains, therefore, open. It is not necessary to make the part G² to H² of 15 the cam-disk absolutely round. It must, however, be so shaped as to prevent a movement of the piston H capable of closing the compensating passage G. Toward the end of the compression period the cam X pushes the roller Y away from the center of the cam-disk and actuates by lever S, rod Q, and lever N O the piston H to make its outward or injection stroke. During this time the roller L' bears against the part H² to J² of the cam-disk. Toward the end of the expansion or 20 working stroke of the working piston the part K² to G² of the cam-disk comes to bear against the roller L' and restores the initial position. It is not necessary that during the injection period—i. e., as long as the cam X moves the roller Y—the roller L' be in permanent contact with the part H² J² of the cam-disk. It is rather preferable to so construct the cam that when the part G² H² 25 comes out of contact with the roller L' the back of the cam-disk H² J² be out of reach of the roller L'. This last-described locking mechanism can also be used for operating four-cycle combustion-engines. It is in such a case only necessary to mount the cam-disk X Z on a separate valve-gear shaft which makes half the number of revolutions of the driving-shaft. It is also possible to fix the cam-disk on the driving-shaft and to 30 operate the piston H twice during the four cycles of the engine. The one stroke at the end of the compression-stroke will effect the injection of the fluid combustible. The other stroke of the piston H at the end of the 35 expulsion-stroke of the driving-piston and commencement of the suction-stroke will be effectless for the working of the machine, for the reason that at this time the chamber F is not yet filled with combustible, this being 40 supplied by pipe D at a subsequent time—

i. e., toward the end of the suction-stroke or even during the compression-stroke.

What I claim as my invention, and desire to secure by Letters Patent of the United States, is—

1. In internal-combustion engines, the combination with the combustion-chamber of an air-chamber, a chamber for the reception of the fluid combustible, both these chambers communicating with each other and with the 75 combustion-chamber, piston adapted to move in the air-chamber, the face of the piston directed to the combustion-chamber having a larger sectional area than the opposite face, means for locking the piston during the 80 compression-stroke of the working piston, and means for releasing and displacing the same about the end of the compression-stroke; all substantially as set forth.

2. In internal-combustion engines comprising a combustion-chamber, a separate air-chamber, a chamber for the fluid combustible, all communicating with each other and piston adapted to move in said chambers, the combination of said piston with a 90 two-armed lever attached to the rod of the piston, and means connected with said lever and operated from the driving-shaft of the engine for locking the piston for part of the revolution of the driving-shaft; all substantially as set forth.

3. In internal-combustion engines comprising a combustion-chamber, a separate air-chamber, a chamber for the fluid combustible all communicating with each other, 100 and piston moving in said air-chamber, the combination of said piston with a two-armed lever connected with the piston-rod thereof, means connected with the driving-shaft of the engine for locking the piston during part 105 of the revolution of the driving-shaft and for releasing the same toward the end of the compression-stroke of the working piston; all substantially as set forth.

4. In internal-combustion engines comprising a combustion-chamber, a separate air-chamber, a chamber for the fluid combustible, all communicating with each other, and piston moving in said air-chamber, the combination of said piston with a two-armed lever and means connected with the driving-shaft for locking said piston during part of the revolution of the driving-shaft, for releasing the same and for operating the instroke of the same; all substantially as set forth.

5. In internal-combustion engines comprising a combustion-chamber, an air-chamber, a chamber for the combustible fluid, all communicating with each other, and piston moving in said air-chamber, the combination of said piston with a two-armed lever, means connected with the driving-shaft for locking the said piston during part of the revolution of the driving-shaft, for releasing the same and means for operating the instroke and out-

stroke of the same; all substantially as set forth.

6. In internal - combustion engines comprising a combustion-chamber, a separate air-chamber, a chamber for the combustible fluid, all communicating with each other, and piston adapted to move in said chambers, the combination of said piston with a two-armed lever, locking-lever acting on the two-armed lever, and tappets actuated from the driving-shaft of the engine which tappets operate the

locking-lever for locking and releasing the two-armed lever and operate the two-armed lever for effecting the instroke of the piston; all substantially as set forth.

In testimony whereof I have hereunto set my hand in presence of two subscribing witnesses.

GUSTAV TRINKLER.
